HIS ATTORNEY.

UNITED STATES PATENT OFFICE

CHARLES L. BRUSH, OF SAN FRANCISCO, CALIFORNIA

CABINET

Application filed March 27, 1931. Serial No. 525,691.

My invention relates to improvements in toilet cabinets and the like wherein a cabinet box having compartments is provided with a compartment having members mounted therein to engage and hold neckties or the like extended in zig-zag fashion within a relatively small area, and to receive articles of apparel of a related nature.

The primary object of my invention is to provide an improved toilet cabinet.

Another object is to provide an improved cabinet having a compartment provided with means to engage and hold neckties in extended form within a relatively small area, and in a conveniently accessible position.

A further object is to provide an improved cabinet compartment having tie supporting and engaging members to prevent crushing or creasing of neckties, and having means to receive and hold collars or other articles of a related use.

A still further object is to provide an improved article of the character described which embodies improved features of structure and arrangement and which affords increased efficiency and utility.

I accomplish these and other objects by means of the improved device disclosed in the drawings forming a part of the present application wherein like characters of reference are used to designate similar parts throughout the specification and drawings, and in which:—

Fig. 1 is a front elevation of my improved cabinet, the door being removed; and

Fig. 2 is a vertical section taken upon the line 2—2 of Fig. 1 in the direction indicated.

Referring to the drawings, my invention comprises a back 1, side members 2 and top and bottom members 3 and 4 respectively defining a cabinet. A door 5 is hingedly connected to the cabinet to normally close the front of the cabinet, and preferably a mirror 6 is mounted above the top member 3 of the cabinet.

Partitions 7 and 8 are mounted within the cabinet to divide the space within the cabinet into a plurality of compartments designated 9, 10, and 11, of various size and shape to

receive toilet articles, or the like, of any desired nature.

One of the compartments, as 9, is provided with a pair of necktie supporting members 12 mounted therein within the upper corners 55 of the compartment. The members 12 may be of any suitable construction, cylindrical pins of substantial diameter and provided with slightly enlarged heads 13 being illustrated as the preferred construction. The members 12 are spaced slightly from the sides and top of the compartment so that a plurality of neckties 14, or other similar articles, may be supported over said members with the end portions of the ties depending along 60 the sides of the compartment.

A member 15 is mounted within the lower central portion of the compartment 9 under which member the middle portions of the ties 14 may be extended to hold the ties in zig-zag 70 fashion within the compartment. The member 15 preferably consists of a hollow pocket forming member of triangular form mounted with its apex downwardly disposed and slightly spaced above the bottom of the compartment, and having its sides diverging upwardly toward the members 12. The top of the hollow member 15 is open to provide access to a pocket 16 adapted to receive collars 75 17 or other articles of apparel.

In operation, the cabinet is mounted upon a wall or other suitable support in any convenient manner, the front of the cabinet being normally closed by the door 5 to enclose the contents of the cabinet. Neckties 14 are 80 inserted into the compartment by extending the middle portions of the ties under the apex of the member 15 and extending the ends of the ties over the pins so that the ends of the ties will be suspended along the sides of the 85 compartment and the middle portions of the ties will extend in zig-zag fashion between the pins, thereby accommodating the full length of the ties within a compartment having relatively small dimensions. The ties 90 are thus held in extended positions with the end portions freely suspended along the sides of the compartment, thereby occupying but little space and guarding the ties against crushing or creasing. At the same time, the 95 100

middle portions of the ties are held flat, thereby tending to preserve the normal thin flat character of that portion of the tie which is engaged within the collar of a wearer. The 5 ties are freely movable around the members 12 so that downward pressure applied to the ends of the ties will tend to straighten out any folds or twisting which may have resulted from the knotting of the tie. The 10 members 12 and the apex of the member 17 are spaced sufficiently from the adjacent walls of the compartment to permit the placing of a number of ties in proximate relation over the members 12 and 15. The 15 The pocket 16 formed by the member 15, affords a convenient receptacle for collars or other apparel. The relatively wide open top of the pocket affords ready access to the pocket and permits collars 17 to be easily 20 inserted or removed as desired, and at the same time affords an efficient means for preserving collars in a clean and uncrushed condition until required.

By incorporating the compartment 9, with 25 its tie engaging members 12 and pocket forming member 15, within a cabinet having compartments adapted to receive various toilet articles or the like, a simple and compact cabinet is obtained whereby ties, collars, and the like may be stored safely and efficiently 30 where they will be conveniently accessible when a user's toilet is being made.

Having thus described my invention, what 35 I claim as new and desire to secure by Letters Patent is:

1. A cabinet comprising a compartment 40 having upper and lower corners; a pair of tie supporting members mounted within the upper corners of the compartment to receive and support ties extended thereover with the ends depending adjacent to the sides of the compartment; and a triangular member 45 mounted within the lower portion of the compartment with its apex downwardly disposed in spaced relation to the bottom of the compartment and with its sides diverging toward the tie supporting members to engage the middle portion of the ties and hold the same extended in zig-zag form within a compartment of relatively small area.

2. A cabinet comprising a compartment 55 having upper and lower corners; a pair of tie supporting members mounted within the upper corners of the compartment to receive and support ties extended thereover with the ends depending adjacent to the sides of the compartment; and a hollow member mounted within the lower portion of the compartment to engage the middle portions of the ties and hold the same extended in zig-zag form within a compartment of relatively small area, said member forming a pocket within the compartment to receive articles of apparel.

3. A cabinet comprising a compartment 60 having upper and lower corners; a pair of

tie supporting members mounted within the upper corners of the compartment to receive and support tie extended thereover with the ends depending adjacent to the sides of the compartment; and a hollow triangular member 70 mounted within the lower portion of the compartment with its apex downwardly disposed and spaced slightly above the bottom of the compartment and the sides of said member diverging upwardly toward the tie 75 supporting members to engage the middle portions of ties extended in zig-zag manner over said supporting members and under the triangular member and thereby hold said ties extended within a compartment of relatively small area, said hollow member forming a pocket within the compartment open at the top thereof to receive articles of apparel.

In witness whereof I hereunto set my signature.

CHARLES L. BRUSH.
